UNITED STATES PATENT OFFICE.

LOUIS G. DE KERMOR, OF EDMONTON, ALBERTA, CANADA, ASSIGNOR TO DELWAY HEATERS, INC., OF NEW YORK, N. Y., A CORPORATION OF NEW YORK.

STEAM-GENERATING MEANS FOR OIL BURNERS.

Application filed August 18, 1927. Serial No. 213,723.

This invention relates to doors or fronts for use with oil burning furnaces employed in the generation of steam for use among other purposes as an atomizing agent and 5 my improvements are directed to a hollow front or door adapted to contain water and to support a burner, my invention further including means carried by the door and continued into the furnace interior, permitting 10 circulation of the water and providing an extended path of travel therefor through the heating zone. Also my invention comprehends the provision of means contained within the hollow front, for collecting the steam generated therein and subjecting it to a superheating or drying process prior to its delivery for service. 15

Still further my invention is inclusive of means provided within the hollow front for 20 the free burning of oil to raise the temperature therein for initially generating steam wherewith to atomize the oil.

Other features and advantages of my invention will hereinafter appear.

25 In the drawing:

Figure 1 is a front elevation of a furnace front or door equipped with my improvements.

Fig. 2 is a sectional view, taken on the 30 line 2—2 of Fig. 1.

Fig. 3 is a sectional view, taken on the line 3—3 of Fig. 1.

Fig. 4 is a front sectional elevation.

Fig. 5 is a section on the line 5—5 of Fig. 35 1, and

Fig. 6 is a horizontal section on the line 6—6 of Fig. 1.

In said views let 1 indicate a furnace and 2 a door hinged thereto at 3. Secured to the 40 door 2 as by screws 4 is a substantially rec-

tangular casing having the back 5, front 6, sides 7, top 8 and bottom 9, the upper portion or chamber A of said casing serving to contain water to be heated, and said portion

45 having a base 10 that is given a corrugated surface to enlarge its heating area. Below base 10 is the firebox B, there being a removable pan 11, placed upon bottom 9, said pan containing moss asbestos or the like which

50 is to be saturated with oil in order to supply the flame for vaporizing the water in the casing.

As an example of heat producing means for use in the fire box a pipe 12 which is ex- 55 tended into the fire box and provided with

a control valve 13, delivers oil through orifices 13' in its length to the pan 11 from a source of supply not herein shown. Obviously I may employ other heating means in the fire box in place of the oil heating means herein shown.

It will be noted in Figs. 2 and 5 that a wall 14 extends upwardly from near the bottom of the fire box at an angle that carries it toward the furnace interior and that 65 a baffle 15 is extended upwardly from said wall, said wall and baffle providing a passageway or flue connection 16 for the ascending products of combustion, which are thereby caused to pass closely against the 70 back 5 of the water chamber A, thereby subjecting the water in said chamber to heat from said products.

The wall 14 also serves as a partition dividing the fire box with its flue connection 75 from a water chamber 17 provided within the furnace; said chamber, which communicates with the water chamber A in the casing, having connected therewith the open ends 18 of return bend pipes or coils 19, 80 that project into the furnace, to be subject to the heat influence of a burner operating therein.

Lying within chamber A, above the water 85 level therein, is a pipe 20 that extends outside said chamber to communicate steam to the point of its desired service (not shown) the end 21 of said pipe within chamber A being open to receive the steam. Preferably the pipe 20 is encased within a larger pipe 90 22, closed at one end 23 and open at its end 24 distant from the reception end 21 of pipe 20, so that steam from chamber A must traverse pipe 22, for drying purposes before passing into pipe 20.

Feed water to the chamber A is supplied through a valve 25, a float 26 being connected with the valve for the operation thereof in accordance with variations in the water level.

In Figs. 1, 3 and 4, I have shown a co- 95 noidal passage-way 27 extended centrally through the casing, its larger end opening into the furnace interior, and its smaller end opening through the casing front 6, 100 105 where it is adapted for the reception of an oil burner (not shown).

It will be appreciated that the essential feature of my invention hereinbefore described consists in the provision of means 110

in a casing carried by a furnace door for initially generating steam therein particularly for use as an atomizing agent in conjunction with an oil burner which may be employed 5 for operating the furnace. Also it will be understood that when steam has thus been generated and the furnace is operating normally the continued supply of steam is provided by means of the heated coils in the 10 furnace, and then the fire in fire box B can be extinguished.

Variations within the spirit and scope of my invention are equally comprehended in the foregoing disclosure.

15 I claim:

1. The combination with an oil burning furnace having a door, of a casing carried by said door, a water chamber and a fire box in said casing, means for burning fuel 20 in said fire box to generate steam in said water chamber, and baffle means to direct the burned products from the fire box, in contacting relation with said casing in their flow to the furnace flue.
- 25 2. The combination with an oil burning furnace having a door, of a casing carried by said door, a partition arranged in said casing and dividing the same into a water chamber and a firebox positioned below the latter, means for burning fuel in said firebox to generate steam in said chamber, a wall extending upwardly adjacent the bottom of said firebox and inclining toward the 30 interior of the furnace to define with the casing wall a passageway to facilitate the con-

tact of the ascending products of combustion against the rear of the water chamber.

3. The combination with an oil burning furnace having a door, of a casing carried by said door, a partition arranged in said casing and dividing the same into a water chamber and a firebox positioned below the latter, means for burning fuel in said firebox to generate steam in said chamber, a wall extending upwardly adjacent the bottom of said firebox and inclining toward the 40 interior of the furnace and baffle means extended from the upper edge of said wall, said wall and baffle means defining with the casing wall a passageway to direct the 50 burned products of combustion from the firebox in contacting relation with said casing in their flow to the furnace flue.

4. The combination with an oil burning furnace having a door, of a casing carried by said door, a partition arranged in said casing and defining a conoidal passageway penetrating the medial portion of said casing, and adapted to receive a burner, a water chamber and a firebox defined by said partition and the casing wall, means for burning fuel in said firebox to generate steam in said water chamber, and baffle means disposed rearwardly of said casing and arranged adjacent the rear portion of said conoidal passageway for directing the burned products from said firebox in contacting relation with 55 said casing in their flow to the furnace flue.

New York, August 8th, 1927.

LOUIS G. DE KERMOR.
